UNITED STATES PATENT OFFICE.

WILLIAM SHERWOOD, OF DETROIT, MICHIGAN.

WATER-INLET VALVE FOR FLUSHING-TANKS.

1,391,860.

Specification of Letters Patent. Patented Sept. 27, 1921.

Application filed October 30, 1920. Serial No. 420,767.

To all whom it may concern:

Be it known that I, WILLIAM SHERWOOD, citizen of the United States, residing at Detroit, county of Wayne, State of Michigan, have invented a certain new and useful Improvement in Water-Inlet Valves for Flushing-Tanks, and declare the following to be a full, clear, and exact description of the same, such as will enable others skilled in the art to which it pertains to make and use the same, reference being had to the accompanying drawings, which form a part of this specification.

My invention relates to an improvement in water inlet valves for flushing tanks shown in the accompanying drawings and more particularly described in the following specification and claims.

One object of this invention is to provide a device which shall be inexpensive, simple in construction and operation and adapted to be regulated to control the delivery of water under various pressures.

A further object of my invention is to provide a positive cut-off against further delivery of water to the tank when refilled, until it is again emptied.

A further object is to provide a device which is noiseless in its action.

With the foregoing and other objects in view which will appear as the description proceeds the invention further resides in the combination and arrangement of parts and in the details of construction hereinafter described and claimed, it being understood that changes may be made in the precise embodiment of the invention herein disclosed without departing from the spirit of the same.

In the drawings accompanying this specification:

Figure 1 is a longitudinal vertical sectional view through a flushing tank showing the inlet valve mechanism in the position it would appear when the water has reached its maximum altitude in the tank and in dotted lines the position of the float lever when the water has been discharged from the tank.

Fig. 2 is a vertical cross sectional view of the inlet valve in the position occupied when "closed."

Fig. 3 is a vertical cross sectional view of the inlet valve when "open" to admit water into the tank.

Fig. 4 is a horizontal cross sectional view taken on or about line 4—4 of Fig. 2.

Referring now to the letters of reference placed upon the drawings:

A, denotes a flushing tank of the usual construction. B, is a discharge valve, its operating mechanism being broken away—as the latter forms no part of the present invention and is not necessary to an understanding of the same.

C, indicates the usual overflow pipe. 65

D, denotes a water inlet pipe extending upwardly from the bottom of the tank and upon the upper end of the pipe is mounted the valve body E, of a water inlet valve.

F, is a reciprocating tubular valve member, housed in the valve chamber, into which is screwed a flaring nozzle or valve G, adapted to be seated against a disk H, held between an annular flange e, integral with the valve body, and a screw threaded plug 70 nut I.

J, is a leather cup-washer held between a flange g, formed on the flaring nozzle or valve, and the end wall f, of the reciprocating tubular valve member F. 80

F' are transverse discharge ports formed in the wall of the member F to direct water into the "after-fill" pipe K, leading to the overflow pipe C.

L, is a forked member slotted to receive 85 the trunnions E' formed integral with the valve body E, on which the forked member oscillates.

M, M, are set screws extending into the reciprocating tubular valve member F, 90 through apertures provided in the forked member, and slots E², in the wall of the valve chamber.

In order that the forked member may be readily assembled with its respective coacting parts, it is slotted as indicated at L' to receive the trunnions E' formed integrally with the valve body. 95

N, is a rod screwed into the forked member on which is mounted a float N'. 100

R, is an adjustable screw projecting downwardly through an ear formed in the valve casing adapted to bear upon an arc-shaped lug L² integral with the forked member L, by adjusting which the tilting action of the 105 float rod may be regulated.

Having thus indicated the several parts by reference letters the construction and op-

eration of the device will be readily understood.

The water in the tank is discharged by lifting the valve B from its seat in the usual manner. Upon the water being discharged from the tank the float N' will assume the position indicated in dotted lines in Fig. 1, thereby shifting the reciprocating tubular valve member F to the position indicated 10 in Fig. 3.

It will now be apparent that water entering the valve chamber from the pipe D, will flow over the disk H, out through the valve or nozzle G, and through the reciprocating 15 tubular valve member F, to a pipe S, connected with the valve member, and thereby into the tank:—the water for the usual “after-fill” passing out through the transverse ports F' to the pipe K, and thence to 20 the overflow pipe C.

Upon the water in the tank reaching a sufficient altitude to raise the float N' to the position indicated in full lines in Fig. 1 the reciprocating valve member will assume the 25 position indicated in Fig. 2,—the valve or flaring nozzle being seated against the disk H, thereby cutting off further flow of water from the pipe D to the tank.

It will be noted that by adjusting the 30 screw R the degree to which the reciprocating tubular valve member F may be opened to admit water to the tank can be regulated.

Having thus described my invention what I claim is:

1. In a device of the character described, 35 a flushing tank; a valve body in said tank; a reciprocating sleeve in said body; an annular bell-shaped valve carried by said reciprocating sleeve; a disk valve-seat supported on an annular flange formed integral with the valve body; a screw threaded plug 40 screwed into the valve body to secure said disk valve-seat in position; a cup washer supported between the bell-shaped valve and reciprocating sleeve; a float lever fulcrumed 45 upon trunnions integral with the valve body,

and detachable means for connecting the float lever with the reciprocating sleeve adjacent to the fulcrum of the float lever.

2. In a device of the character described, 50 a flushing tank; a valve chamber in said tank; a reciprocating sleeve, having transverse ports; an annular valve having a flaring end, connected with said sleeve and adapted to be seated near the upper end of 55 the valve chamber; a discharge pipe connected with the lower end of the reciprocating sleeve and opening into the tank; a water inlet pipe connected with an inlet port opening into the valve chamber below the 60 open flaring end of the valve; an “after-fill” pipe leading from the valve chamber to deliver water passing through the transverse ports of the reciprocating sleeve to an overflow pipe; and a float lever connected with 65 the reciprocating sleeve and fulcrumed upon the valve chamber adjacent to its connection with the sleeve.

3. In a device of the character described; 70 a flushing tank; a valve body in said tank; a reciprocating sleeve in said body; an annular valve having a flaring end carried by said reciprocating sleeve; a disk valve seat supported on an annular flange formed integral with the valve body; a screw 75 threaded plug screwed into said body to secure said disk valve seat in position; a cup-washer supported between the annular valve and the reciprocating sleeve; a float lever fulcrumed upon trunnions integral with the 80 valve body; and a pair of opposing set screws carried by the reciprocating sleeve for connecting the float lever with the reciprocating sleeve adjacent to the fulcrum 85 of the float lever.

In testimony whereof, I sign this specification in the presence of two witnesses.

WILLIAM SHERWOOD.
